PENCIL ERASER

Clarence F. Norlin, Chicago, Ill.

Application April 28, 1945, Serial No. 590,927

8 Claims. (Cl. 120—38)

1

This invention relates to a pencil eraser more particularly adapted for releasable attachment with a mechanical pencil and which has a double utility of being connected with such a pencil and reversible to expose a fresh eraser after the first portion thereof has been used.

There are numerous types of erasers adapted for connection with pencils and in most cases such erasers require a considerable amount of waste material for accommodating the attaching means by which such erasers are connected with pencils of various types. Furthermore, it is usually the practice to produce such an eraser having only one effective erasing head or portion that requires replacement each time such portion has been utilized.

It is one of the main objects of the present invention to produce an eraser which will require a relatively small amount of waste rubber to effectively carry the securing means by which such eraser is attached to a pencil.

Another object in combination with the above noted advantageous feature is that the eraser is produced with a double head having a dual capacity eraser active under the same fastening means and definitely more efficient than the normal single head erasers of the kind described.

Another feature of the present eraser design is that the rubber itself together with a band encircling the same forms a resilient means through the coaction of the rubber and the band which will expand the attaching means for securement with a suitable coacting pencil cap preformed for holding the eraser of the present construction.

All other objects and advantages inherently embodied in the eraser of the present design shall hereinafter appear in the following detailed description of a preferred and modified construction thereof having reference to the accompanying drawings.

In the drawings:

Fig. 1 is a side elevational view of a conventional mechanical pencil embodying the eraser constructed in accordance with the principles of the present invention;

Fig. 2 is an enlarged fragmentary sectional portion of the eraser end of the mechanical pencil illustrated in Fig. 1 and as viewed substantially along the line 2—2 therein;

Fig. 3 is an end elevational view of the eraser per se as removed from the pencil;

Fig. 4 is a cross-sectional view of the eraser as taken substantially along the line 4—4 in Fig. 3; and

2

Fig. 5 is a view similar to Fig. 2 illustrating a modified construction of eraser as attached to a pencil.

It is to be understood that the present eraser may be applied to most any form of pencil, but is preferably for use in connection with a mechanical type of pencil inasmuch as the greatest utility is inherently found in such use. In mechanical type of pencils it is usually the practice to provide a magazine or lead chamber in the upper portion of the pencil and the eraser is used in the capacity of a plug or closure means for preventing the leads from dropping out of the magazine end of such a pencil. By making an eraser of a construction which is readily removable to permit access to the extra leads the facility and usefulness of such an eraser is much more efficient and convenient.

Referring now to Figs. 1 and 2, a pencil is indicated generally at 6 having a cap 7 in the form of the hollow sleeve frictionally secured adjacent the shoulder 8 at the upper open end 9 of the pencil body 10. The extra lead magazine is indicated at 11 with spare lead 12 therein. The eraser per se is indicated by the reference numeral 13 and comprises a relatively elongated rubber eraser portion 14 with the ends 15 and 16 thereof providing a double ended pencil eraser.

A band 17 in the form of a sleeve encircles the mid portion of the eraser 14. The band 17 is preferably of resilient material continuous excepting for a slit 18 shown in Figs. 3 and 4. The band 17 is secured to the midpoint of the eraser 14 by circumferentially crimping the terminal edges 19 and 20 to bite into the eraser at the ends of the band 17.

The band 17 normally occupies the open position illustrated in Figs. 3 and 4 and is so held by the expansion of the rubber portion of the eraser within the band. Furthermore, the length of the band 17 is relatively short in order that a relatively small amount of the eraser 14 will be wasted after both ends of the latter have been effectively used while attached to the pencil.

Another advantageous feature is the function of the band 17 and its cooperation with the inwardly crimped edge 21 of the cap 7 forming detent means for positioning the band 17 in counter sunk relation within the pencil exposing the ends 15 and 16 of the rubber 14 to provide one end for active use while storing the other end within the upper well or the pencil cap itself.

Under normal conditions the band 17 will be expanded under the action of the rubber 14 to dispose the outer diameter of the band in a po-

sition wherein the same will be substantially coincident with the inner diameter of the pencil cap 7. The eraser is therefore applied to the pencil by means of contracting the band 17 compressing the entrapped rubber and inserting the same into the open end of the cap 7 until the groove 22 formed centrally about the periphery of the band is aligned with the inwardly crimped open edges of the band 17. When the band is moved into this position particularly illustrated in Fig. 2, the band will expand under the internal resiliency of the rubber and snap into place with the concealed half of the band 17 in circumferential contact with the inner surface of the cap 7 of the pencil.

Referring again to Fig. 4 it should be noted that the circumferentially crimped ends 19 and 20 of the band 17 are made to oppose longitudinal movement of the rubber in either direction relative to the band 17. Moreover, when the rubber eraser unit is held in position relative to the pencil as illustrated in Fig. 2, the exposed usable portion of the rubber will normally be urged toward the pencil and its holding band 17 but such movement will be stopped directly by the particular crimped edge of the band 17 that is adjacent the exposed rubber portion of the eraser.

It should also be understood that although the eraser shown in Fig. 2 is directly connected with an auxiliary portion of the pencil in the form of the band 17, that it is also readily possible to form a portion of the pencil body per se in such a manner as to also cooperate with the band 17 and including a cap that will be operative to enter the groove 22 upon the band similar to the detent means 21 to directly hold such eraser in releasable position capable of subsequent inversion when one end of the usable rubber eraser portion has been worn away.

Referring now to Fig. 5, it is seen that the pencil end has been modified to hold the cap 7 in a lower position with respect to the end of the pencil body 10 containing the extra lead chamber 11. In this construction, the upper end 21 of the cap 7 is crimped in the same manner as in the preferred form illustrated in Fig. 2 to provide detent means for latching engagement within the peripheral groove 22 of the band 17. In this case, however, the peripheral groove is provided by crimping the central peripheral portion of the band upon the rubber to thereby prevent relative movement between the rubber 14 and the band 17. Also, the band 17 in this case is preferably made with relatively flat shouldered ends 23 and 24 which are used for abutment purposes to directly cooperate to seat upon the flat shouldered end 25 of the upper portion of the pencil body 10. In this case therefore, the rubber 14 houses the unused portion thereof directly within the upper hollow end of the pencil body itself.

The latter construction explained and disclosed in Fig. 5 incorporates the use of a centrally crimped band, such band also being split as shown in Fig. 3 and which pencil eraser band is provided in such proportions as to length and diameter for resting or abutting the upper edge 25 of the pencil body when such band and its rubber are seated within the detent means of the pencil cooperating with the band groove.

In either of the constructions illustrated attention is directed to the fact that the circumferential grooves 22 in the bands 17 also provide grip means for a fingernail to aid in retracting the eraser unit for purposes of inversion to bring

the fresh eraser tip into usable relation or for the purpose of expelling the band when both of the rubber tips have been worn away.

Other variations and modifications are contemplated in the disclosures described having particular reference to the construction, form, or combination of parts shown. Such changes or modifications shall be directly controlled by the latitude and purview of the appended claims.

10 I claim:

1. An eraser for attachment with the hollow cap structure of a pencil comprising a rubber, a resilient band secured centrally about said rubber, said band having a recess therein, said hollow cap structure having inwardly formed detent means adapted for engagement within said band recess to releasably attach the band to said pencil with one portion of the rubber disposed in usable exposed relation with respect to the pencil.

20 2. An eraser for attachment with the hollow cap of a pencil, comprising a rubber, a resilient band secured centrally about said rubber with the latter protruding from both ends thereof, circumferentially said band having a located recess 25 midway of the ends thereof, and detent means on said hollow cap to engage within said recess to releasably secure said band to said pencil with one end of said rubber disposed in usable exposed relation with respect to the pencil.

30 3. A replaceable eraser for connection with a hollow pencil cap, comprising an elongated rubber, an expandable band secured about the rubber midway of the ends thereof and urged radially outwardly by said rubber into a predetermined expanded position, said band having a central circumferential depression therein, and said cap having a continuous projection thereon for engagement within said band groove upon expansion of said band subsequent to contraction thereof for insertion into said hollow cap and into operative relation with respect to said continuous projection thereon.

40 4. A replaceable eraser for connection with a pencil cap, comprising a rubber, a split band disposed about the mid point of said rubber and urged radially outwardly into a predetermined position by said rubber, said band having a central groove encircling the same between the ends thereof, said band being substantially of the same outside diameter as the internal diameter of said cap when in said predetermined expanded position, and detent means projecting inwardly toward the axial centerline of said cap and adapted to engage within said band groove after the band is contracted against the rubber to allow insertion of said band into said cap and subsequent expansion upon alignment of said cap detent means and said band groove.

50 5. A replaceable eraser for connection with a pencil cap, comprising a rubber, a split band disposed about the mid point of said rubber and urged radially outwardly into a predetermined position by said rubber, the ends of said band being crimped into said rubber to prevent relative movement between said band and rubber longitudinally, said band having a central groove encircling the same between the ends thereof, said band being substantially of the same outside diameter as the internal diameter of said cap when in said predetermined expanded position, and detent means projecting inwardly toward the axial centerline of said cap and adapted to engage within said band groove after the band is contracted against the rubber to allow insertion of said band into said cap and subsequent expansion

upon alignment of said cap detent means and said band groove.

6. A replaceable eraser for connection with a pencil cap, comprising a rubber, a split band disposed about the midpoint of said rubber and urged radially outwardly into a predetermined position by said rubber, a central groove encircling said band midway between the ends thereof, said band being substantially of the same outside diameter as the internal diameter of said cap when in said predetermined expanded position, and detent means extending inwardly toward the axial centerline of said cap to engage within said band groove after the band is contracted against the rubber to allow insertion of said band into said cap and subsequent expansion upon alignment of said cap detent means and said groove, said band being positioned by said cap detent means and the band of such length to abuttingly engage and rest upon the upper face of the pencil body to further steady said rubber.

7. A replaceable eraser for connection with a hollow pencil cap seated upon the pencil body with the latter extending into said cap, said eraser comprising a rubber, an expansible member tightly encircling said rubber, and cooperative detent means carried by said member and the pencil cap respectively to hold the eraser in position upon

the pencil, said expansible member having one end thereof directly engaging an integral portion of said pencil body to abut the latter to steady said member and the connected rubber with respect to the cap.

8. An eraser for attachment with the hollow cap structure of a pencil comprising a rubber, a resilient band secured centrally about said rubber, said band having a recess therein, said hollow cap structure having inwardly formed detent means adapted for engagement within said band recess to releasably attach the band to said pencil in a position exposing one portion of said rubber in usable relation with respect to said cap, and guide means carried by said cap and adapted to engage said eraser structure to steady same during use, said detent means preventing in and out displacement of said eraser structure while in normal use.
